UNITED STATES PATENT OFFICE.

WINFRED MUDGE BROOKS, OF EAST ORANGE, NEW JERSEY, ASSIGNOR TO E. J. BROOKS & CO., OF NEW YORK, N. Y., A CORPORATION OF NEW YORK.

SHACKLE-SEAL.

1,152,143.

Specification of Letters Patent.

Patented Aug. 31, 1915.

Application filed June 8, 1915. Serial No. 32,925.

To all whom it may concern:

Be it known that I, WINFRED MUDGE BROOKS, a citizen of the United States of America, and a resident of East Orange, in the State of New Jersey, have invented a new and useful Improvement in Shackle-Seals, of which the following is a specification.

This invention relates to shackle seals and the object is to provide a simple, positive and efficient locking and sealing device by means of which the ends of the shackle can be locked firmly together, free from danger of accidental unsealing and secure against tampering.

Two sheets of drawings accompany this specification as part thereof, in which like reference characters denote like parts throughout.

Figures 1, 2 and 3 show side, front and back views respectively of the improved shackle seal, unfastened, with one form of the improved locking device in place; Fig. 4 shows a side view of the same locked, with the locked ends of the shackle in section; Figs. 5, 6 and 7 show a side, front and back view of the seal having another type of the locking device and special means for preventing longitudinal displacement of the shackle ends; Figs. 8, 9, 10, 11, 12, 13 and 14 show various forms of the locking device; Figs. 15, 16 and 17 show side front and back views of the shackle seal with modified forms of the locking device; Figs. 18 and 19 show side and back views of the seal with a double ended locking device; Fig. 20 shows an end view of Fig. 16; Figs. 21 and 24 show side views unlocked and locked of the seal having a locking device adapted to prevent longitudinal displacement of the shackle ends, while Figs. 22 and 23 show front and back views of the same locked; Fig. 25 shows a side view of a device similar to Fig. 21 having additional means on one shackle end to prevent longitudinal displacement; Fig. 26 shows a section on the line 26—26 of Fig. 25 the device being locked. Figs. 27 to 33 inclusive show further modifications of the locking device within the scope of the invention and Figs. 34 and 35 show side views unlocked and locked using the locking device shown in Fig. 33; Figs. 36, 37 and 38 show side and front views of the improved seal in which an ordinary nail is used as the locking means, the details of

securing the nail in place by swaging being shown in section in Fig. 38. Fig. 39 shows a fractured locking device, the fracture being at the transverse nicks hereinafter described.

Referring to the drawings, *a* represents the shackle, *d* and *d'* longitudinal casing grooves located near the ends of the shackle and adapted to coincide when said ends are brought together and form a casing for the locking end or ends of the locking device, *o* and *o'* represent holes located at the ends of the casing grooves through which the parts of the locking member pass, *b* is the crown of the locking member, *m* represents the locking ends of same and *n* a modified form of *m* adapted to secure the locking device to one shackle end preliminary to leaving the factory and *v* transverse notches cut in the inner side of the locking member at points of proposed bending, *c* and *c'* represent stiffening grooves in the shackle ends and *e* in Figs. 2 and 3 represent weakening holes to prevent bending and unbending of shackle ends, *p* in Figs. 5, 6 and 7 represents transverse grooves in the shackle ends adapted to coincide and prevent longitudinal displacement of said ends after locking, and *p'* in Figs. 21 to 32 represents a hump in the locking end of the locking device adapted to prevent the withdrawal of the shackle end after sealing by such a displacement. The shackle end is shown bent up for a similar purpose at *p''* in Figs. 25 and 26. In Figs. 36 and 37 the nail used for the locking member is swaged on as shown at *n'* in Fig. 38. The weakening holes *e* shown in Figs. 2 and 3, the transverse grooves *p* in the shackle ends as shown in Figs. 5, 6 and 7 and the humps *p'* in the locking member shown in Figs. 24 to 32 are adapted to be used in each of the various species shown or may all be combined in one seal as desired.

The invention consists essentially in sealing together the ends of a flat shackle seal, suitably stiffened, by means of a simple loop of wire nicked at the points of bending upon its inner side and capable of being bent in one direction only, viz: toward said nicks, without breaking. A suitable casing groove is provided to receive the locking ends of the loop and protect same from accidental displacement after sealing.

The seal as it leaves the factory consists

of a flat shackle having the sealing member affixed to one end by a nicked and bent end as shown in Figs. 1, 5, 21 and 34, by a head and bur as shown in Fig. 38 or by merely having the fastening ends forced through the appropriate holes *o* in one shackle end as in Fig. 18.

In operation the shackle is passed through the staples or other fastening devices which are to be sealed and the locking member *m* is passed through the hole *o'* in the other shackle end. The two shackle ends are then brought together closely, the stiffening and casing grooves *c*, *c'* and *d*, *d'* and the cross grooves *p* where used, all coinciding and allowing for a snug close union of the two ends. The locking member *m* is then bent down at and toward the notch in its face and pressed home in the casing *d'*. In the type shown in Fig. 18 where there are two locking ends *m* the operation is similar with regard to each. In the type shown in Figs. 34 and 35 the locking member *m* is provided with a series of notches *v* in its side toward which it is turned transversely of the shackle ends forming a locking coil with said notches on its inner side.

Any attempt to unfasten the shackle ends by unbending the sealing member will result in the fracture of the latter at its transverse notches with resulting disclosure. Both the crown and the ends of the locking members can be flattened and suitably embossed, a desirable system being to provide both the shackle and the sealing member with the same serial number, thus preventing substitution.

Modifications for particular purposes will readily suggest themselves to those skilled in the art.

Having thus fully described my invention I claim:

1. A seal having in combination, a flat shackle having longitudinal stiffening grooves, longitudinal casing grooves near the ends thereof, a locking member attached to one end of said shackle having transverse notches at the points of proposed bending, a hole or holes near the end of the other end of said shackle adapted to receive the locking member, all substantially as hereinbefore set forth.

2. A seal having in combination a flat

shackle, a wire sealing member having transverse nicks on its inner side disposed at points of proposed bending, means for securing said loop to one shackle end, holes in the other shackle end adjacent to the locking ends of said loop and adapted to permit the passage of said ends and means for preventing the accidental disturbance of said locking ends after sealing.

3. A seal having in combination a flat shackle, a wire sealing member having transverse nicks on its inner side disposed at points of proposed bending, means for securing said sealing member to one shackle end, a hole in the other shackle end adapted to permit the passage of the end of the sealing member, longitudinal grooves in the shackle ends adapted to coincide and form a casing for the sealing member after it is bent down and transverse grooves crossing said casing grooves in the shackle ends, also adapted to interlock and prevent longitudinal displacement of the shackle ends, after sealing.

4. A seal having in combination a flat shackle, longitudinal stiffening and casing grooves near the ends thereof, the grooves on one end being adapted to interlock with those on the other upon the two ends being brought together, a sealing member having a flattened and embossed head and two locking members bent at right angles to said head, transverse nicks on the inner sides of said bends, holes in the shackle ends adapted to receive the locking members, weakening holes in the stiffening grooves and means to prevent the longitudinal displacement of the shackle ends after sealing.

5. In an improved shackle seal, a flat shackle, a sealing member having transverse nicks and locking ends commencing at said nicks, a hump upon one of said locking ends, holes in the ends of said shackle adapted to permit the passage of said locking ends, a longitudinal casing groove similarly located on each of said shackle ends and adapted to coincide and form a housing for said locking ends after sealing and means for stiffening said shackle ends.

WINFRED MUDGE BROOKS.
